UNITED STATES PATENT OFFICE.

EDWARD DES NOYERS AND HENRY VOHL, OF WEST HOBOKEN, NEW JERSEY.

CLOTHES-LINE PULLEY.

SPECIFICATION forming part of Letters Patent No. 777,717, dated December 20, 1904.

Application filed November 11, 1903. Serial No. 180,766.

To all whom it may concern:

Be it known that we, EDWARD DES NOYERS and HENRY VOHL, citizens of the United States, residing at West Hoboken, in the county of Hudson and State of New Jersey, have invented new and useful Improvements in Clothes-Line Pulleys, of which the following is a specification.

Our invention relates to new and useful improvements in pulleys especially adapted for use in connection with clothes-lines; and its object is to provide a simple and light device of this character which can be readily fastened to a wall or detached therefrom and which is provided with means whereby when it is rotated the clothes-line can be moved backward and forward upon the supports provided therefor.

With the above and other objects in view the invention consists in the novel construction and combination of parts hereinafter more fully described and claimed, and illustrated in the accompanying drawings, showing the preferred form of our invention, and in which—

25 Figure 1 is an elevation of a clothes-line, its pulley, and supporting means. Fig. 2 is an enlarged vertical section through the pulley, and Fig. 3 is a horizontal section through the pulley.

30 Referring to the figures by numerals of reference, 1 is a support having a pulley 2 connected thereto, upon which is arranged an endless clothes-line 3. This line is wound one or more times about a drum 4, which is secured, by means of a key 5, to a shaft 6, journaled in side plates 7. A crank 8 is fastened to the shaft at one end, and a pin 9 engages the other end of the shaft, and this pin and the crank prevent longitudinal movement of

40 the shaft in relation to the side plates. Similar parallel ears 10 extend from the side plates 7 and are connected by means of a cross-pin 11, which is riveted or otherwise fastened within the ears, and loosely mounted on this cross-pin is a tongue 12, having laterally ex-

tending ears 13 at its free end. A bracket 14 is fastened to a wall or other suitable support 15 and has parallel hooks 16 formed upon its outer face, said hooks being spaced apart a sufficient distance to permit the tongue 12 to 5° be inserted therebetween and the lugs 13 placed in engagement with the hooks. It will be understood that when the drum 4 is rotated by means of the crank 8 the clothes-line will be moved backward or forward, as desired. The tongue 12 can be readily placed in or removed from engagement with the hooks 16, and it will be seen, therefore, that the pulley can be easily attached to any suitable support provided.

55 In the foregoing description we have shown the preferred form of our invention; but we do not limit ourselves thereto, as we are aware that modifications may be made therein without departing from the spirit or sacrificing 65 any of the advantages thereof, and we therefore reserve the right to make such changes as fairly fall within the scope of our invention.

Having thus described the invention, what is claimed as new is—

70 In a device of the character described, the combination with a bracket having parallel hooks integral therewith; of a tongue loosely mounted between the hooks, laterally-extending lugs upon the tongue and detachably engaging the hooks whereby a swinging movement of the tongue is permitted, a cross-pin extending through one end of the tongue, side plates, ears thereon connected by the cross-pin and at opposite sides of the tongue, a shaft 75 journaled in the side plates, a crank thereon, and a drum secured to the shaft and between the side plates.

80 In testimony whereof we affix our signatures in presence of two witnesses.

EDWARD DES NOYERS.
HENRY VOHL.

Witnesses:

JOHN SINGER,
MORRIS EICHMANN.
